Louis, Mo., assignors to Railway Devices Com-
pany, St. Louis, Mo., a corporation of Missouri

Application February 19, 1943, Serial No. 109,586

Term of patent 14 years

To all whom it may concern:

Be it known that we, Sterling H. Campbell and Frank H. Pietzsch, citizens of the United States of America, residing at the city of St. Louis, State of Missouri, have invented a new, original, and ornamental Design for a Transitional Angle Cock Holder, of which the following is a specification, reference being had to the accompanying drawing, forming a part thereof.

In the drawing Figure 1 is a front view of a

transitional angle cock holder showing our new design; Figure 2 is a side view; Figure 3 is a section taken on the line 3—3 of Figure 1; and Figure 4 is a rear view.

We claim:

The ornamental design for a transitional angle cock holder, as shown.
